UNITED STATES PATENT OFFICE.

ADOLPH F. PRAHM, OF ST. LOUIS, MISSOURI.

LANTERN.

No. 863,872.

Specification of Letters Patent.

Patented Aug. 20, 1907.

Application filed March 25, 1907. Serial No. 364,270.

To all whom it may concern:

Be it known that I, ADOLPH F. PRAHM, a citizen of the United States of America, residing in the city of St. Louis and State of Missouri, have invented certain 5 new and useful Improvements in Lanterns, of which the following is a full, clear, and exact description, reference being had to the accompanying drawings, forming part of this specification.

My invention relates to a spring actuated lifting device for lanterns so constructed that the globe of the lantern is held in lowered position against the action of the lifting springs by means associated with the ventilator tube of the lantern, which when released, permits the lifting action of the springs.

15 Figure I is a view partly in side elevation and partly in vertical section of my lantern. Fig. II is a horizontal section taken on line II, II Fig. I. Fig. III is a horizontal section taken on line III, III, Fig. I. Fig. IV is a vertical section taken through the upper or venti- 20 tilating members of the lantern. Fig. V is an elevation of a modified form of crank rod that may be used in my lantern.

1 Figure I designates the font of my lantern, supplied with a vertical burner 2 and surmounted by air tubes 3 that

25 terminate at their upper ends in an air chamber 4.

5 is a ventilator tube that is slidably fitted within the air chamber 4 and is surmounted by a hood 6, provided with a central perforation 7.

8 designates the globe supporting disk that is adapt- 30 ed to fit the dome of the burner 2 between which and the ventilator tube 5 the globe A is seated.

9 is a guard ring that extends horizontally around the globe A and is mounted in the air tubes 3.

B designates a pair of lift springs for service in con- 35 nection with the globe supporting disk 8. Each of these lift springs comprises a main coil 10 located along side of an air tube 3 an arm 11 extending transversely through the air tube and terminating in an upwardly extending arm formed at its extremity with an eye or 40 single coil 12 which is fitted to the guard wire 9 at the side of the air tube opposite to that at which the coil of the spring is located, and also an arm 13 that extends downwardly from the main coil 10 of the spring to a position beneath the rim of the globe supporting disk 45 and then upwardly through an orifice in the globe supporting disk in the form of a hook.

By the described construction of the lift springs their attachment to the frame members of the lantern, namely, air tubes and the guard ring and the application 50 of the arms 13 of the springs to the globe supporting disk, I furnish a strong, durable and efficient globe

supporting disk lifting means that is adapted to be placed under tension when the globe of the lantern is lowered to the burner of the lantern and one that is therefore always in readiness for globe lifting action 55 when the parts to be hereinafter described and by which the globe is held depressed are released.

14 designates a crank rod rockingly mounted in the air chamber 4 of the lantern through which it extends in a horizontal direction (see Figs. I, II and IV) this 60 rod being provided with a central crank arm or loop 15 located within the ventilator tube 5 and with a crank handle 16 located exteriorly of the air chamber 4.

17 is a pull-rod loosely connected at its lower or inner end to the crank arm or loop of the crank rod 14 65 and having its upper or outer end extended through the perforation 7 and the ventilator tube hood 6 and terminating in a coil 18 that prevents inward movement of the upper end of the pull-rod through said hood. The crank rod by its connection to the hood 70 of the ventilator tube is designed for service in effecting a downward movement of the ventilator tube within the air chamber 4 and to permit of this movement of the ventilator tube said tube is provided with slots 5' through which the crank rod extends. 75

It will be readily seen that in the use of my lantern, the globe A is depressed from an elevated position when the crank rod 14 is rotated to effect a downward pull upon the pull-rod 17 due to said pull-rod uniting the crank rod to the hood of the ventilator 80 tube and the globe being fitted to the lower end of said ventilator tube. As the globe moves downwardly it carries with it the supporting disk 8 and the arms 13 of the lift springs B are moved downwardly to be in readiness for lifting action when the globe is to be 85 again elevated.

For the purpose of retaining the crank rod 14 in a set position after the globe has been depressed, until it is to be again elevated, I provide a notch 4' in a projecting portion of the air chamber 4 of the lantern 90 and in the path of movement of the crank 16 and into which said crank may enter as seen in the drawings Figs. II and IV, this notch being preferably produced in a bead 4^a at the bottom of the air chamber.

In Fig. V, I have shown a modification of the crank 95 rod, in which said rod, designated by the character 14' is provided with a solid crank arm 15' instead of the rod having the crank loop 15 and this solid crank arm contains an eye in which the pull-rod 17 is fitted.

I claim:

1. In a lantern, the combination of a font, a frame surmounting said font, a globe supporting disk, a globe

on said disk, lift springs secured to said frame and fitted to said disk, a ventilator tube slidably fitted in said frame and engaging said globe, and a crank rod rockably mounted in said frame and having connection with said ventilator; said rod having a crank handle exterior of the lantern frame and said frame being notched to receive said crank handle, substantially as set forth.

5. 2. In a lantern, the combination of a font, a frame surmounting said font, a globe supporting disk, a globe

on said disk, lift springs secured to said frame and fitted to said disk, a ventilator tube slidably fitted in the upper end of said frame, a crank rod rockably mounted in said frame, and a pull rod uniting said crank rod to the top of said ventilator tube, substantially as set forth.

10 ADOLPH F. PRAHM.

In the presence of—

LILY ROST,

HOWARD G. COOK.
